The ornamental design for bonnet for agricultural tractor, as shown and described.

DESCRIPTION

FIG. 1 is a perspective view of the bonnet for agricultural tractor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom view thereof; and,

FIG. 8 is another perspective view thereof.

The part of the photograph shown in a coarse dot pattern, along with the broken-line perimeter, illustrates a portion of the tractor that forms no part of the claimed design.
